UNITED STATES PATENT OFFICE.

ALBERT J. LARCHER, OF HARVEY, ILLINOIS, ASSIGNOR TO WYMAN-GORDON CO., OF WORCESTER, MASSACHUSETTS, A CORPORATION OF MASSACHUSETTS.

FORGING METHOD AND APPARATUS.

Application filed April 24, 1922. Serial No. 556,187.

To all whom it may concern:

Be it known that I, ALBERT J. LARCHER, a citizen of the United States, residing at Harvey, in the county of Cook and State 5 of Illinois, have invented certain new and useful Improvements in Forging Methods and Apparatus, of which the following is a specification.

This invention relates to metal working 10 but more particularly to the manufacture of crankshafts, axles, and other similar parts, and has for its principal objects to provide a simplified and improved method of production and a superior product.

15 Further important objects of my invention are to provide a new and improved method of increasing the cross-sectional area of portions of a bar of metal, to economize metal, to eliminate reheating, to avoid 20 stretching of the metal, to eliminate folding back of the metal upon itself, to improve the grain of the metal, to avoid the use of rolls or rolling dies, to materially reduce the cost of the forming operation, and to 25 permit the forming of a crankshaft with integral counterweights.

The many other objects and advantages will be better understood by reference to the following specification when considered 30 in connection with the accompanying drawings illustrating the application of my invention to the manufacture of crankshafts for reciprocating engines.

Referring to the drawings:—
35 Fig. 1 is a perspective view of the upper and the lower dies.

Fig. 2 is a section on the line 2—2 of Fig. 1.

Fig. 3 is a vertical longitudinal section 40 through the dies for forming the blank, the stock being in position for the first blow.

Fig. 4 is the same as Fig. 3, at the finish of the first blow.

Fig. 5 is a side elevation of the stock at 45 the completion of the first blow.

Figs. 6 to 10 are transverse sections on the correspondingly numbered lines of Fig. 5.

Fig. 11 is the same as Fig. 3, at the start of the second blow.

50 Fig. 12 is the same as Fig. 3, at the completion of the second blow.

Fig. 13 is a side elevation of the stock at the end of the second blow.

Figs. 14 to 18 are transverse sections on the correspondingly numbered lines of Fig. 55 13.

Fig. 19 is the same as Fig. 3, illustrating the position of the dies and form of the stock after the final blow.

Fig. 20 is a side elevation of the stock 60 after the final blow.

Figs. 21 to 25 are transverse sectional views on the correspondingly numbered lines of Fig. 20.

Fig. 26 is a vertical longitudinal section 65 through the edging dies showing the formed blank in position for the start of the edging operation.

Fig. 27 is the same as Fig. 26 with the edging operation partially completed. 70

Fig. 28 is the same as Fig. 26 at the completion of the edging operation.

Fig. 29 is a top plan view of a modified form of lower die block designed to produce a crankshaft having integral counter- 75 weights.

Fig. 30 is a bottom plan view of the upper die block operating with the lower die of Fig. 29.

Fig. 31 is a vertical longitudinal section 80 of the forming dies of Fig. 29, showing the stock in position for the first blow.

Fig. 32 is the same as Fig. 31, showing substantially the position of the dies and the form of the stock at the completion of 85 the first blow.

Fig. 33 is the same as Fig. 31, at the start of the second blow.

Fig. 34 is the same as Fig. 31, at the completion of the second blow or final blow. 90

Fig. 35 is an elevation of the counter-weighted crankshaft blank at the completion of the forming operation.

Fig. 36 is a section on the line 36—36 of Fig. 35. 95

Fig. 37 is a vertical longitudinal section of the edging dies or edger, showing the blank in position for the start of the operation.

Fig. 38 is the same as Fig. 37 at the completion of the edging operation, and 100

Fig. 39 is a plan view of the completely

formed crankshaft with the integral counterweights thereon.

The manufacture of crankshafts may be considered to be divided into two parts or stages, the forming or shaping of the crankshaft, and the finishing of the same. In the first stage the crankshaft is completely formed with pins, bearings and cheeks in proper position. In the second stage the formed shaft is machined and otherwise prepared for assembly in an engine. The present invention relates particularly to the first or forming stage.

The initial step in the manufacture of a crankshaft is the forming of the blank. In order to provide a blank having the proper distribution of metal for the formation of the offsets or throws it has usually been the custom to upset a heated bar in a machine provided for the purpose. The number and position of these upsets in the bar depend largely on the design of the particular shaft. This upsetting operation is slow and costly as the bar must be reheated after each upset is formed. On this account it has been common practice to depend upon one large upset formed at or near the center of the bar and the blank thus formed has been drawn out or stretched in an edger. A tong hold was generally formed on one end of the blank prior to submission to the edger in order to facilitate handling. In addition to the disadvantages already set forth, the upsetting of the bar materially weakens the metal by folding it back upon itself. The drawing out or stretching of the metal in the edging operation still further reduces its strength. Another method of forming the blank consists in taking stock having an initial cross-sectional area equal to the necessary enlargements on the formed blank and reducing the remaining portions of the stock by drawing. This method is wasteful of stock and generally requires the use of more than one hammer. A heavy hammer is required in the drawing operation.

Instead of upsetting or drawing the stock in the manner described, I enlarge the bar at one or more points to provide the necessary accumulations of metal by striking the bar between forging dies which perform at one operation all the necessary movements of metal including the forming of the tong hold. No reheating is necessary by this method and the entire forming of the crankshaft may be accomplished at a single heating. This method makes it equally simple to provide one or many accumulations of metal in the bar, and the metal may be so disposed that practically no stretching will occur in the subsequent operations. In the operation comprising the present invention metal in the stock is simultaneously drawn inwardly toward a central area to be enlarged from outlying areas disposed on opposite

sides thereof, as distinguished from the mere reshaping of the metal already included in such central area.

The drawings are intended to clearly illustrate the principles of my improved method and suitable apparatus for performing the same. In Fig. 1 is shown an upper block 50 and a lower block 51, each of which contains three dies or die cavities, the dies 52 for forming the blank, the edging die or 75 edger 53, and the shaping die 54. The present invention relates to the dies 52 and their association with the edging and shaping dies. The particular form of these dies will naturally vary for different designs of 80 crankshaft, and different designers might even prefer different dispositions of the metal in the blank but the principles remain the same in all cases.

The cavity in the die 52 consists of an 85 elongated recess having depressions 55 at the points where accumulations of metal in the blank are desired. The remaining or intervening portions 56 of this recess preferably slope slightly toward one of these depressions 55 so that when the stock is struck between these dies the metal will be caused to flow toward the depression. This slope can be best seen in Fig. 3 of the drawings.

The operation of forming the blank is 95 performed by striking a bar of steel a succession of blows between the dies 52. The bar is preferably rolled, rotated or turned about its axis through an angle of approximately 90° after each blow. The number of 100 blows necessary to complete this operation will vary with different bars so that the illustration in the drawings of the progress of the work at different stages should be understood to be merely explanatory. 105

Considering the operation in detail, the stock or bar of steel 57 is placed on the lower die in the position indicated in Fig. 3, and struck by the upper die. At the completion of this blow the form of the bar 110 and position of the dies will be substantially as illustrated in Fig. 4. A side elevation of the bar at this stage is shown in Fig. 5, and the various transverse sections in Figs. 6 to 10. It should be noted that a general 115 flow of the metal has started and that some has already entered the depressions.

The bar is now rolled, rotated or turned about its axis through an angle of approximately 90° from the position at the completion of the first blow, replaced on the lower die 52 in its new position, as indicated in Fig. 11, and again struck. The approximate position of the dies and form of the bar at this stage are illustrated in Figs. 12 to 18. 125

The operation of rolling, rotating or turning the bar through an angle of approximately 90° and restriking in the dies is continued until the blank is completely formed 130

(Fig. 19). While this forming operation might be shortened by striking heavy blows of the hammer, it has been my experience that a moderate flow of the metal will produce the best crankshaft.

The formed blank is now placed on the lower edging die 53 in the manner indicated in Fig. 26 and struck by the upper die. The movement of the metal observed in the intermediate position (Fig. 27) is interesting as showing that practically no stretching of the metal takes place. The bar moves by a combined sliding and bending action and the metal is pushed or caused to flow by the faces of the dies, as distinguished from the usual pulling or drawing out of the metal generally occurring in this operation. The final position is indicated in Fig. 28.

The crankshaft is then removed from the edging dies or edger and struck between the usual shaping dies 54. In the present embodiment these dies complete the first stage of the crankshaft construction, as the particular shaft is of the four-throw type in which all pins and bearings are in the same plane. In the case of a six-throw crank the shaft would preferably be formed with the pins and bearings in one plane, as in the four-throw, and then subjected to positioning dies in the manner described in Letters Patent of the United States No. 1,403,696 granted to me January 17, 1922, although any other suitable method of forming the crankshaft from the blank might be used.

At the completion of the shaping operation in the dies 54, the crankshaft would preferably be submitted to the usual trimming dies (not shown) to remove the flash and preferably restruck thereafter in the shaping dies to true the pins, bearings and cheeks.

The dies 52 perform simultaneously the movement of the metal substantially longitudinal of the axis of the bar to provide the necessary enlargements and form the tong hold. No cooling of portions of the bar is necessary for this operation and, upon the completion of the rolling, rotating or turning operation, the formed bar is ready to be presented successively to the edger and the shaping dies without further reheating or, in other words, the crankshaft is completely formed from the bar at a single heating.

It has been found that when the crankshaft is produced by the method herein described, the grain of the metal is practically parallel with the center line of the shaft throughout its length. This is particularly advantageous and greatly increases the strength of the shaft. Practically no stretching of the metal takes place and the action in the edger is one of bending and squeezing rather than of pulling. The squeezing or pushing of the metal causes it to flow into

the various depressions in the dies. By enlarging portions of the bar to the necessary size, as distinguished from the method of using a bar initially of the size of the enlargements and reducing the remaining portions, a substantial saving in materials and labor is provided.

My improved forging method is particularly advantageous in the manufacture of crankshafts with integral counterweights. In modern shop practice, counterweights have generally been attached to the shaft by bolting, welding, shrinking or a variety of other methods on account of the almost prohibitive cost of all known methods of forming these parts integral or in one piece, but it has been generally recognized that the shaft with integral counterweights is far superior to one having the counterweights attached. Heretofore in the manufacture of crankshafts with integral counterweights, the blank has generally been formed by upsetting or drawing. Some of the disadvantages of these methods have been set forth in connection with the previous embodiment. By my improved method the necessary accumulations of metal for the offsets or throws and the counterweights are economically provided in the blank at a single operation even where large counterweights are required.

Referring to Figs. 29 to 39 inclusive of the drawings, the upper die block 200 and the lower die block 210 are provided with corresponding dies or die cavities which in the present embodiment consist of dies 220 for forming the blank, edging dies or an edger 230, and shaping dies 240. The cavity in the dies 220 consists of an elongated recess having depressions 250 at the points where accumulations of metal in the blank are required. The remaining portions 260 of the die cavities preferably slope toward one of these depressions for the purpose set forth in connection with the previous embodiment.

The forming of the blank is accomplished by alternately striking and turning, rotating or rolling the bar of steel between the dies 220 in the manner previously described. The number of blows necessary to complete the forming of the blank will vary with different bars so that the illustration in the drawings of the progress of the work at different stages should be understood to be merely explanatory.

Considering the operation in detail, the stock or bar 270 of steel is initially placed on the lower die in substantially the manner illustrated in Fig. 31 of the drawings and struck by the upper die. Fig. 32 shows substantially the position of the dies and the form of the stock at the completion of the first blow. The stock is then rolled, rotated or turned about its axis through an angle preferably of approximately 90° and re-

70

95

105

110

115

120

125

130

placed in its new position on the lower die in the manner indicated in Fig. 33. It is then restruck by the upper die. This operation of alternately rolling, rotating or turning and restriking the stock should be continued until the blank is completely formed, as indicated in Figs. 34 to 36.

The formed blank is next placed upon the lower edging die 230 in the manner indicated in Fig. 37 and struck by the upper die. At the completion of the edging operation the crankshaft is in the form shown in Fig. 38.

The edged crankshaft is then placed in the shaping dies 240 in the usual manner. After being struck in the shaping dies the crankshaft is trimmed and trued in the manner described.

In the forming of the blank, enlargements 280 are provided at the necessary parts of the bar and this metal is forced by the action of the edging dies into the corresponding depressions 290 in these dies to form lateral projections 300 which are shaped by the depressions 310 of the dies 240 into integral counterweights 320 (Fig. 39). The counterweighted crankshaft is produced by my improved method as simply and easily as a shaft without counterweights and no difficulty is encountered in forming counterweights of large size.

The particular dies shown in the drawings are designed to produce a crankshaft of the four-throw, three bearing type, but any other form of crankshaft may be produced in the same manner.

While I have confined the illustration and description of my improved method to the manufacture of crankshafts, it is obvious that it is equally applicable to the production of a very large number of other articles, such as axles or cam shafts.

I claim as my invention:

1. The method of enlarging the cross-sectional area of a portion of a bar of metal which consists in heating the bar, and subjecting the adjoining portions of the heated bar on opposite sides of the portion to be enlarged to substantially transverse pressure 45 between the working faces of relatively reciprocating die members to cause metal in said adjoining portions to flow toward the portion to be enlarged, the portions of said faces contacting with the adjoining portions 50 of said bar being inclined toward the portion to be enlarged.

2. The method of enlarging the cross-sectional area of a portion of a bar of metal which consists in heating the bar and rolling the heated bar between relatively reciprocating die members having inclined working faces exerting a transverse pressure on the portions of the bar on opposite sides of the portion to be enlarged to cause metal 60 in said opposite portions to simultaneously

flow substantially longitudinally of the axis of the bar toward the portion to be enlarged.

3. The method of forming a projection on one side of a bar of metal which consists in subjecting the bar to transverse pressure between relatively reciprocating die members having a depression in one of said members corresponding substantially in contour to the projection to be formed and inclined surfaces on opposite sides thereof leading to said depression to cause metal in outlying areas of the bar to be moved substantially longitudinally of the axis of said bar toward said depression to fill the same. 70

4. The method of forming a projection on one side of a heated bar of metal which consists in subjecting the bar to transverse pressure between relatively reciprocating die members having a depression in the 85 working face of one of said members corresponding in contour to the projection to be formed and inclined surfaces leading to said depression on opposite sides thereof to cause metal in the bar to be simultaneously moved from outlying portions of the bar toward said depression to fill the same. 90

5. Forging apparatus comprising relatively reciprocating die members having a depression formed in the working face of 95 one of said members, portions of said working face on opposite sides of said depression sloping toward said depression to cause metal of the stock disposed opposite said sloping portions to be simultaneously moved 100 inwardly toward said depression to fill the same.

6. Forging apparatus comprising relatively reciprocating die members having working faces forming an elongated die cavity, and provided with a transverse depression intermediate the ends of said cavity, portions of the die cavity on opposite sides of said depression sloping toward said depression to cause the metal of adjoining portions of the stock to be simultaneously moved inwardly along the die cavity toward said depression to fill the same. 105

7. The method of making a crank shaft which consists in enlarging the cross-sectional area of one or more portions of a heated bar of metal by subjecting the bar to transverse pressure between relatively reciprocating die members to form the blank, and forming offsets in the blank. 115

8. The method of making a crank shaft which consists in enlarging the cross-sectional area of one or more portions of a heated bar of metal by subjecting the same to transverse pressure between relatively reciprocating die members to form the blank, forming offsets in the blank, and submitting the blank to shaping dies. 125

9. The method of making a crank shaft which consists in enlarging the cross-sec- 130

tional area of a portion of a heated bar of metal by simultaneously moving in toward the portion to be enlarged metal from portions of the bar on opposite sides thereof to form the blank, forming the throws in the blank, and shaping the blank.

10. The forging method which consists in heating a bar of metal, enlarging the cross-sectional area of one or more portions thereof by subjecting the heated bar to lateral pressure between inclined faces of relatively reciprocating die members to form the blank, subjecting the blank to edging dies to form one or more offsets therein, and shaping the edged blank between shaping dies.

11. The method of making a crankshaft which consists in enlarging the cross-sectional area of one or more portions of a heated bar of metal by rolling the bar between relatively reciprocating die members to form the blank, forming the throws in the blank, and shaping the formed blank.

12. The method of making a counter-weighted crankshaft blank which consists in heating a bar of metal, and enlarging the cross-sectional area of the bar at substantially the counterweight positions by subjecting the bar to lateral pressure between relatively reciprocating die members.

13. The method of making a crankshaft with integral counterweights which consists in heating a bar of metal, enlarging the cross-sectional area of the bar at substantially the counterweight positions by subjecting the heated bar to lateral pressure to form the blank, subjecting the blank to edging dies to form the throws and counterweights, and shaping the edged blank.

14. The method of making a crank-shaft with integral counterweights which consists in heating a bar of metal, enlarging the cross-sectional area of certain portions of the bar including the counterweight positions by rolling the heated bar between relatively reciprocating forging dies, breaking down the blank in an edger to form the throws and counterweights, and submitting the edged blank to shaping dies.

15. The method of enlarging the cross-sec-

tional area of a section of a bar of metal 50 which consists in subjecting the adjoining sections of the bar on opposite sides of the section to be enlarged to substantially transverse pressure between the working faces of die members to cause the masses of metal 55 composing said adjoining sections to flow longitudinally of the axis of the bar toward the portion to be enlarged, the portions of one of said faces contacting with said adjoining sections being inclined toward the 60 section to be enlarged.

16. Forging apparatus comprising relatively reciprocating die members having a cavity formed in the working face of one of said members and gradually tapering channels in said face extending from opposite sides of said cavity to cause the mass of metal of the stock disposed opposite said channels to simultaneously flow inwardly toward said cavity to fill the same. 70

17. Forging apparatus comprising relatively reciprocating die members having a cavity formed in the working face of one of said members and gradually tapering channels in said face extending from opposite sides of said cavity to cause the metal of relatively remote portions of the stock to flow inwardly in opposite directions toward said depression to fill the same. 75

18. The method of forming an enlargement in an intermediate point in the length of a bar of initially substantially uniform cross section which consists in simultaneously effecting elongatory movements of separated spaced portions of said bar of substantial length in opposite directions so as to cause the said elongatory movements to oppose each other thereby to cause compression by means of said elongatory movements while permitting expansion of such compressed portion to occur, said elongatory movements being effected by transverse pressure initially applied to portions of said bar remote from the point to be enlarged and subsequently applying said transverse pressure progressively toward the point at which the enlargement is to be formed. 95

ALBERT J. LARCHER.
